UNITED STATES PATENT OFFICE.

LOUIS F. DESPRES, OF LEBANON, NEW HAMPSHIRE.

LAMP WRENCH.

1,404,349.

Specification of Letters Patent. Patented Jan. 24, 1922.

Application filed April 16, 1921. Serial No. 462,064.

To all whom it may concern:

Be it known that I, LOUIS F. DESPRES, a citizen of the United States, residing at Lebanon, in the county of Grafton and State 5 of New Hampshire, have invented certain new and useful Improvements in Lamp Wrenches, of which the following is a specification, reference being had to the accompanying drawings.

10 This invention relates to wrenches and particularly to a wrench for use in connection with lamps or headlights of automobiles.

An object of the invention is to provide a 15 wrench of this character wherein the lens supporting frame of the headlight may be readily applied and removed.

Another object is to provide a device of 20 this character which readily unfastens the lens supporting frame without the assistance of any other tool.

A still further object of the invention is 25 to provide a device of this character capable of embracing the lens supporting frame, for the purpose of removal without causing damage or marring the frame in any way.

A still further object of the invention is 30 to provide a device of this character consisting of a single length of material adapted to embrace the lens supporting frame of the headlight and wherein the end portions of the members are arranged to be connected for the purpose of binding the number on the frame.

35 With these and other objects in view the invention consists in the improved construction and arrangement of parts to be hereininafter more particularly described, fully claimed and illustrated in the accompanying drawings in which:—

Figure 1 is a front elevation of a headlight showing the invention applied,

Figure 2 is a perspective view of the wrench,

45 Figure 3 is a top plan view of the structure shown in Figure 1,

Figure 4 is a fragmentary perspective view showing the position of one of the stop fingers.

50 Referring to the drawings 5 designates a body member or jaw constructed of resilient material substantially rectangular in cross sections and may be made in any length desired. The end portions 6 and 7 of the jaw 55 are extended toward each other so as to form the jaw member into a band. The inner sur-

face of the band is provided with anti-slipping material 9, such as rubber which may be secured to the band in any desired manner. Projecting from one edge of the 60 jaw at spaced intervals and inwardly of the band formed by the jaw is a plurality of stop fingers 8 which limit lateral movement of the jaw member when the same is being applied. The inner face of each of the stop 65 fingers is provided with a lining similar to the anti-slipping material 9 of the band so as to prevent marring of the object with which the wrench is engaged.

The end portion 6 of the jaw member is 70 slightly enlarged and provided with an opening 10, one portion of the opening being substantially flattened as at 11 and of a length corresponding to the width of the end portion 7 of the jaw. The end portion 75 7 of the jaw is slightly reduced and provided with a handle 13, said handle and end portion being arranged to extend through the opening 10 of the end portion 9, the end portion 7 being then extended back from the 80 portion 11 of the end portion 6 so as to bind the jaw in engagement with the lens supporting frame A of a headlight. The binding engagement of the jaw with the frame can be regulated according to the distance 85 the end portion 7 passes beyond the end portion 6.

It is of course obvious that when the handle 13 is moved after being passed through the opening 10, that the lens supporting 90 frame will also respond in view of the binding engagement of the jaw therewith. When it is desired to disengage the wrench from the frame A, it is not necessary to disengage the end 7 from the end 6, but simply 95 relieve the binding engagement of the jaw on the frame by releasing the handle 13, whereupon the entire jaw may be moved laterally of the frame and thereby disengaged.

The fingers 8 serve to limit the movement 100 of the band laterally of the frame A so that there is no danger of the wrench slipping off the frame when being applied, or when in use.

From the foregoing it will be readily seen 105 that this invention provides a novel form of wrench capable of being used in connection with all cylindrical members such as the lens frame of headlights, jar covers, or the like, wherein it is necessary to rotate these members in order that they may be removed or applied. Another important feature of the 110

device is that no adjustment is necessary in order to accommodate the jaw member to the size of the work, and very little physical strength is necessary in order to loosen the 5 firmly secured lens supporting frame and the operation is accomplished without scratching the frame or distorting the same in any manner.

What is claimed is:—

- 10 1. A wrench of the character described consisting of a resilient strip, one end portion of said strip being enlarged and having an enlarged slot extending substantially laterally of the strip, the opposite end of the 15 strip being reduced, said reduced end portion being arranged to extend through the slot, and anti-slipping means carried by the inner face of the strip.

2. A wrench of the character described consisting of a resilient strip, one end portion of said strip being enlarged and having a substantially triangular slot, the base portion of said triangular slot being disposed adjacent the extremity of said end of the strip, the opposite end of the strip being reduced, said reduced end portion being arranged to extend through and engage the base portion of said triangular slot, and anti-slipping means carried by the inner face of said strip, said means terminating adjacent the enlarged and reduced end portions of the strip. 20 25 30

In testimony whereof I hereunto affix my signature.

LOUIS F. DESPRES.
